US00D996904S

(12) **United States Design Patent** (10) **Patent No.:** **US D996,904 S**
(45) **Date of Patent:** **** Aug. 29, 2023**

(54) **BEVERAGE GLASS**

(71) Applicant: **Lincoln Kayiwa**, Helsinki (FI)

(72) Inventor: **Lincoln Kayiwa**, Helsinki (FI)

(**) Term: **15 Years**

(21) Appl. No.: **29/786,877**

(22) Filed: **Jun. 3, 2021**

(30) **Foreign Application Priority Data**

May 21, 2021 (EM) 008550792-0009

(51) **LOC (14) Cl.** **07-01**

(52) **U.S. Cl.**

USPC **D7/523**; D11/90

(58) **Field of Classification Search**

USPC D7/514, 523, 509, 510, 392.1, 396.2,
